United States Patent

Des. 235,956
Patented July 22, 1975

235,956

DRAWER

Thomas S. Noneman, Thomas R. Smith, and John B. Stokes, Bryan, Ohio, assignors to Tomco Plastic Inc., Bryan, Ohio

Filed Aug. 2, 1973, Ser. No. 385,046

Term of patent 14 years

Int. CL D6—06

U.S. CL D6—191

Figure 1

Figure 2

Figure 3

Figure 4

FIG. 1 is a rear perspective view of a drawer incorporating our new design;

FIG. 2 is a rear view thereof;

FIG. 3 is a right side view thereof; and

FIG. 4 is a bottom view thereof.

The side not shown is the same as the side illustrated. The interior and the front are plain and unornamented.

We claim:

The ornamental design for a drawer, as shown and described.
